CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate display screen or portion thereof, and form no part of the claimed design. The broken lines within the peripheral broken lines illustrate portions of the graphical user interface which forms part of the claimed design.

UNITED STATES PATENT AND TRADEMARK OFFICE
CERTIFICATE OF CORRECTION

PATENT NO. : D967,839 S
APPLICATION NO. : 29/776213
DATED : October 25, 2022
INVENTOR(S) : Jonathan Dascola et al.

Page 1 of 3

It is certified that error appears in the above-identified patent and that said Letters Patent is hereby corrected as shown below:

On the Title Page

Replace Title Page with attached Title Page.

(57) DESCRIPTION, Column 2, Lines 3-4:

-The peripheral dashed broken lines illustrate display screen or portion thereof, and form no part of the claimed design.-

Should be:

--The peripheral dashed broken lines illustrate a display screen or portion thereof, and form no part of the claimed design.--.

In the Drawings

The drawing sheet was printed upside-down. Attached herewith is the correct drawing sheet.

Signed and Sealed this
Twenty-eighth Day of February, 2023
